DIMERIZATION PROCESS

David R. Carley and Walter E. Foster, Baton Rouge, La., assignors to Ethyl Corporation, New York, N. Y., a corporation of Delaware

No Drawing. Application December 6, 1954,
Serial No. 473,487

8 Claims. (Cl. 260—533)

This invention relates to a process for the preparation of dimerized products and more particularly, but not exclusively, to the dimerization of butadiene in the presence of sodium or potassium to produce a dialkali metal octadiene adduct. The invention also relates to the further reaction of this disodiooctadiene adduct (or potassium adduct) with carbon dioxide to produce dibasic acids or with other reagents to form corresponding difunctional products.

The dimerization of butadiene in the presence of an active ether and metallic sodium or potassium has been reported previously (see Walker patent, U. S. 2,352,461). This prior method involves reacting the butadiene with the alkali metal in the presence of an active ether and simultaneously, or in a subsequent step, reacting the resultant product with carbon dioxide to form dibasic acids. In this process, the metal is employed in a solid form (in strips) and is pressed against a rotating scraper provided in the reaction vessel, the metal being abraded gradually during the progress of the reaction. This reaction is conducted at a temperature of between about 0° to 30° C. and upon carbonation produces a mixture of acids from which it is difficult to isolate individual acids in any degree of purity. In the prior process, if the alkali metal and butadiene were allowed to react to a substantial extent before admitting carbon dioxide to the reaction mixture, the final mixture of acids contained relatively large amounts of the higher dibasic acids. In addition, the use of this technique results in a considerable amount of polymerization of the butadiene, rather than the desired dimerization to form a disodio-octadiene adduct (or potassium adduct). Upon carbonation of this material, a complex mixture of many acids is produced rather than the desirable and valuable 10-carbon atom dibasic acids.

It is accordingly an object of this invention to provide an improved dimerization process for conjugated polyenes, such as butadiene. Another object is to provide a process which minimizes or avoids the formation of higher derivatives or polymeric materials. Another object is to provide a process which will selectively produce a dimerized aliphatic unsaturated hydrocarbon adduct with an alkali metal, such as sodium or potassium, which can be subsequently carbonated, or otherwise reacted, without the prior problem of undue by-product formation. Another object is to provide a process which employs a highly active dispersed form of an alkali metal and is adapted to maintain it in highly reactive condition throughout the course of the reaction. Other objects and advantages of this invention will become more apparent from the following description and appended claims.

We now have found that butadiene and other conjugated polyenes can be dimerized selectively, without the formation of any appreciable higher molecular weight by-products, such as polymer, to form a low molecular weight aliphatic unsaturated hydrocarbon adduct with an alkali metal in exceptionally high yields, of the order of 80 percent or higher. This is accomplished if the reaction

2

is carried out, in the usual solvent system, using the alkali metal in highly dispersed form in the presence of a diaryl ketone, such as benzophenone. In contrast to the product obtained by using strips of sodium and carried out in the absence of the diaryl ketone, the reaction product of the present invention is almost entirely a dimerized adduct of the alkali metal and contains only very small quantities, if any, of higher molecular weight derivatives. Moreover, the low molecular weight adduct of this invention is relatively stable and can be reacted, even after relatively long periods of time, with other reactants, such as carbon dioxide, to give very useful and valuable relatively low molecular weight products.

In prior processes, as noted above, it was necessary to use simultaneous addition of carbon dioxide to minimize somewhat the formation of higher molecular weight products. Using simultaneous addition, it was necessary to employ excess quantities of alkali metal due to deactivation of the alkali metal by the carbon dioxide. Thus, better utilization of alkali metal can be achieved in the present process than with prior processes.

More particularly, the process of this invention for producing an aliphatic hydrocarbon adduct with an alkali metal, such as sodium or potassium, comprises adding a conjugated polyene, such as butadiene, to finely dispersed alkali metal in a reaction medium containing at least about 0.0001 percent of a diaryl ketone and above about 300 weight percent of a solvent, both based upon the weight of the alkali metal, at a temperature below about 50° C., the solvent being selected from the group consisting of ethers, acetals and tertiary amines.

In carrying out this process, the diaryl ketone is added to the alkali metal prior to an appreciable reaction with the conjugated polyene. It can be added directly to the alkali metal, frequently dispersed in an inert solvent, or can be added to the active solvent, either before or after addition of the dispersed alkali metal.

In batch operation, the conjugated polyene should be added to the alkali metal, and should be added over a sufficient period of time to prevent a build-up of an excessive unreacted concentration, which condition favors the formation of polymer or other higher molecular weight compounds. This polyene addition can be either continuous or can be periodic. In any event, the total period of addition should generally be at least 1/2 hour and preferably at least 2 hours.

The reaction can also be conducted in a continuous fashion in which event the polyene and alkali metal are continuously added in the preferred proportions. In using a continuous reaction, there is no tendency to build up an undue concentration of polyene and therefore the formation of high polymers is minimized or eliminated.

The polyenes useful for this invention should have between 4 and 16 carbon atoms. Typical examples are butadiene, pentadiene, hexadiene, octadiene, decadiene and pentadecadiene. Substituted dienes are also suitable for this invention. Typical examples of alkyl substituted dienes are isoprene, 2-ethyl butadiene, dimethyl butadiene, tertiary butyl-butadiene, 2-methyl-pentadiene, 3-methyl-pentadiene, 2-hexyl-pentadiene, 2-methyl-octadiene, 1,3- and 2-methyl-octadiene-2,4, 2-ethyl decadiene-1,3, 3-ethyl decadiene-2,4, cyclopentadiene, alloöcimene, and the like.

Typical examples of aryl substituted dienes are 1-phenyl butadiene, 2-phenyl butadiene, 1,4-diphenyl butadiene, naphthyl butadiene, and the like. Styrene also is suitable and for purposes of this invention is included as a conjugated polyene.

Total quantity of polyene added to the reaction medium is normally not appreciably greater than stoichiometric quantities, based upon the alkali metal, i. e., 1 mole of polyene per mole of alkali metal, and generally is employed in a molar ratio of not less than 0.4:1. Prefer-

ably, the polyene is employed in a molar ratio of between 0.7:1 and 0.95:1, polyene:alkali metal.

The polyene can be added to the alkali metal reaction mixture either as a gas or liquid, preferably diluted with the reaction solvent or with an inert gas such as nitrogen. The degree of dilution is not critical but is advantageous to use at least one part of diluent by volume per part of polyene.

The principal alkali metals suitable for this invention are sodium and potassium. While the other alkali metals are useful, they are generally less desirable for economic reasons. In addition to the use of the pure metals noted, alloys or mixtures of these metals can be employed with other alkali metals or with alkaline earth metals.

The alkali metal must be used as a fine dispersion having an average particle size normally not more than 50 microns. It is preferred to use an alkali metal having an average particle size below about 15 microns. In general, the finest particle size obtainable produces the best results.

The alkali metal dispersion is normally made in an inert organic solvent such as iso-octane, heptane, decane, purified kerosene, other non-reactive petroleum fractions, di-n-butyl ether or similar materials. In some cases the ether, acetal or amine solvent can be used advantageously as the dispersion medium. When employed, the quantity of dispersion medium is not critical and can range from about equal quantities based upon the alkali metal to a quantity equal to the weight of the solvent employed. The dispersion can be made by any suitable well-known method. It is generally preferred to use a high speed agitator and a small quantity of a dispersing agent, such as oleic acid, linoleic acid, dilinoleic acid, carbon black, etc. Normally the dispersion is made at an elevated temperature and is thereafter allowed to cool to room temperature or lower prior to use in the process of this invention.

The diaryl ketones useful in the present invention are compounds in which the aryl groups are phenyl, naphthyl, biphenyl, or any of the higher condensed or non-condensed polynuclear radicals or any combination of these radicals. Typical examples of diaromatic ketones are benzophenone, phenyl naphthyl ketone, dinaphthyl ketone, phenyl biphenyl ketone, dibiphenyl ketone, phenyl terphenyl ketone, biphenyl naphthyl ketone, diterphenyl ketone and cyclic ketones, such as fluorenone.

In general, the concentration of the diaromatic ketone should be controlled to prevent the formation of by-products. If the ketone is used in excess, it not only wastes quantities of the reactants but the by-products tend to contaminate the product. It is most frequently convenient to control the quantity of diaromatic ketone needed in the process by adding sufficient quantities to the reaction medium, prior to the addition of polyenes, to give a reaction mixture having a color characteristic of the alkali metal ketyl of the particular ketone used, such as blue or purple with benzophenone. This color normally is dissipated after beginning the addition of the butadiene or other polyenes to the reaction mixture. In general, this concentration is not less than about 0.0001 nor more than 10 weight percent, based upon the weight of the alkali metal, but a more preferred range is between 0.001 and about 1.0 weight percent. Excessive quantities, as noted above, reduce the yield of the desired adduct through formation of by-products.

The solvents suitable for use in the present invention, as pointed out above are the ethers, acetals and tertiary amines. A preferred group of ethers for use in the present invention include both aliphatic mono- and polyethers. The preferred monoethers have a $\text{CH}_3-\text{O}-$ group and have an oxygen:carbon ratio not less than 1:4. Typical examples of these preferred monoethers are dimethyl ether, methyl ethyl ether, methyl isopropyl ether, methyl n-propyl ether or mixtures of these ethers. The above ethers also can be mixed with hydrocarbon solvents, if desired.

The preferred polyethers are ethylene glycol diethers,

such as methyl methyl, methyl ethyl, ethyl ethyl, methyl butyl, ethyl butyl, butyl butyl, butyl lauryl; diethylene glycol ethers, such as methyl methyl, ethyl ethyl, ethyl butyl and butyl lauryl; trimethylene glycol ethers, such as dimethyl, diethyl, methyl ethyl, etc.; glycerol ethers, such as trimethyl, dimethyl ethyl, diethyl methyl, etc.; and cyclic ethers, such as dioxane, tetrahydrofuran, methyl glycerol formal, dimethylene pentaerythrite.

A wide variety of acetals also can be used in the present invention. Typical examples of suitable acetals are methylal, 1,1-dimethoxy ethane, 1,1-dimethoxy propane, 1,1-dimethoxy butane, glycol formal, methyl glycerol formal, etc. The preferred acetals are methylal, glycol formal and methyl glycerol formal.

A wide variety of tertiary amines are suitable for this invention including both aliphatic and aromatic amines. The preferred tertiary amines for use in this invention are trimethyl amines, dimethyl ethyl amine, tetra methyl methylene diamine and n-methyl morpholine.

The active solvent should have a high degree of purity to avoid contamination of the alkali metal surface. The amount of active solvent employed in the reaction mixture can be varied considerably without departing from the scope of the invention. The amount used generally will depend on the particular reactants and solvent used. In general, the use of from 100 to 2,000 cc. of solvent per gram mole of sodium, i. e. not less than 300 percent by weight of the alkali metal is recommended as a suitable reaction dilution. When a diluent, e. g. an inert hydrocarbon dispersant for the alkali metal, is used along with the active solvent, sufficient active solvent should be present to have an active promoting effect upon the reaction. In general, it is preferred to use a reaction medium which contains a weight of active solvent at least as great as the weight of any co-present diluent.

The temperature of the reaction is preferably maintained below about 50° C. but above the melting point of the solvent system. With most reaction media, it is preferred to maintain the temperature below about 0° C. Highly desirable reactions can be obtained as low as -80° C.

The reaction mixture throughout the course of the reaction should be agitated vigorously to insure complete mixing of the polyene with the dispersed alkali metal mixture and to facilitate heat transfer in the system.

The process can be conducted either in a batch or continuous manner. When carried out continuously, it is preferred to employ a tube-type reactor. In the latter case, the polyene and sodium dispersion in the active ether can be fed continuously in the desired proportions to the inlet end of the tube-type reactor.

The reaction should be conducted in an inert atmosphere to exclude oxygen, moisture, carbon dioxide, and other impurities which would be reactive toward the alkali metal adduct, the reaction preferably being carried out employing a dry nitrogen atmosphere or other inert gas.

In addition to carbonation of the alkali metal adduct, the adduct can be reacted with many other Grignard type reactants, having carbonyl, thionyl, and nitrile groups to form highly desirable products. Typical examples of such reactants are sulfur dioxide, benzene sulfonyl chloride, thionyl chloride, formaldehyde, acetone, ethylene oxide, propylene oxide, acetonitrile, propionitrile, and the like. For example, the organo alkali metal adduct can be reacted in typical Grignard type reactions with sulfur dioxide to form disulfonic acids with formaldehyde or epoxides to give diols, with cyanogen chloride to give dinitriles or used generally as a Grignard type reactant in reactions with esters, acid anhydrides, aldehydes, ketones, and nitriles. In addition, reactions with oxygen and halides, particularly chlorides, bromides and iodides, are suitable and, for purposes herein, are considered as common Grignard reactions.

The alkali metal adduct also can be reacted with organic compounds, such as alkylaryl, acetylenic, nitrile, and

cyclodienyl compounds to effect transmetalation and the metalated product can thereafter be reacted with any of the Grignard-type reactants, noted above.

The temperature of the subsequent reaction is generally not critical. However, with certain of the reactions discussed, such as carbonation, it is necessary to conduct the reaction in the cold, below about 0° C. and preferably below -30° C.

The following examples illustrate our invention but are not intended to in any way limit the scope thereof. In 10 these examples, all parts are by weight.

Example I

Dimethyl ether (140 parts) was charged to a reaction vessel maintained below -50° C. and equipped with a stirrer, a reflux condenser, a thermometer and a gas inlet tube adapted to extend below the surface of the reaction mixture. The dimethyl ether employed was previously purified by stirring with sufficient quantities of sodium and benzophenone to form the blue ketyl. The ether then was distilled from this mixture. Sodium (12.5 parts), previously dispersed in purified kerosene and having an average particle size of about 8 microns, was added to the ether, under an atmosphere of dry nitrogen. Benzophenone (0.019 part) was added to this mixture and produced a blue color. The temperature of the system then was raised to -30° C. A total of 22.2 parts of butadiene, diluted with an equal volume of dry nitrogen, was fed continuously to the reactor over a period of three hours. The reaction mixture changed from a blue to a light yellow color within about 10 minutes after the addition was started. During the entire period, the reaction mixture was agitated vigorously, and agitation was continued for about forty-five minutes after completion of addition of the butadiene.

Following completion of the above dimerization reaction, 80 parts of dry isoctane were added to the reaction mixture. The mixture was thereafter carbonated by pouring the same onto a large excess of crushed solid carbon dioxide. Following vaporization of the excess carbon dioxide, 100 parts of water were added to the reaction mixture to destroy the unreacted sodium. The resulting reaction mixture then was permitted to separate into an aqueous solution of the product salts (unsaturated 10-carbon atom dibasic acid salts) and a hydrocarbon fraction.

The product acids were thereafter recovered from the aqueous phase by acidification and extraction with ether. These unsaturated acids were thereafter saturated by a conventional hydrogenation process at room temperature in ether solution, using a platinum oxide catalyst.

The total yield of crude acid was 33.7 parts having an average neutralization equivalent of 104 (corresponding to the theoretical of 101 for 10-carbon dibasic acids). This acid mixture, upon separation, contained about 30 percent sebacic acid; 52 percent 2-ethyl suberic acid; 10 percent 3-ethyl suberic acid; and 2,2'-diethyl adipic acid; and the remainder contained principally valeric and pelargonic acids.

The hydrocarbon layer was distilled, obtaining only 60 2.2 parts of polymer.

Example II

Example I is repeated except that the dimerized adduct is treated with gaseous formaldehyde instead of with carbon dioxide. The formaldehyde reaction is conducted at 30° C. under sufficient pressure to retain the dimethyl ether solvent in the reaction medium, using a total of 18 parts of formaldehyde in gaseous form. The formaldehyde is added continuously over a one-hour period, using agitation throughout the reaction. The decadienediol product mixture is recovered by flashing the solvent at essentially atmospheric pressure, reacting the remaining sodium with an excess of ethyl alcohol, and separating by fractional distillation of the product.

Example III

Example I is repeated except that the adduct is reacted with ethylene oxide to produce dodecadienediols. In this example, ethylene oxide vapor (25 parts), diluted with dry nitrogen, is passed, over a period of one hour, into the reaction mixture, maintained at -30° C. The solvent is distilled and the sodium reacted with an excess of ethyl alcohol. The mixture is thereafter fractionated to obtain the diol product.

Example IV

Example I was repeated except that the adduct was reacted with toluene to effect transmetalation and the benzyl sodium so formed was thereafter reacted with carbon dioxide to form phenyl acetic acid. In this example, the sodium initially was dispersed in 18.5 parts of toluene. Following the formation of the disodiooctadiene adduct, an additional 88 parts of toluene were added. This mixture then was heated to distill the methyl ether solvent and the reaction mixture was stirred at 100-105° C. for two hours. The reaction mixture thereafter was cooled to 0° C. and poured on solid carbon dioxide. 30.6 parts of phenyl acetic acid were obtained from the aqueous fraction. The hydrocarbon fraction was distilled, leaving a residue of only 1.0 part of polymer.

Example V

Example I was repeated except that dioxane was employed as the active solvent and the temperature of the reaction was 18° C. Also, the sodium was dispersed directly in the dioxane solvent, using 220 parts of dioxane and 12.5 parts of sodium. The average particle size of the sodium was about 10 microns. Benzophenone (0.005 part) was added to the sodium dispersion. Butadiene (14.5 parts) was added over a period of 2 1/4 hours. The initial blue color changed to light tan after commencing addition of butadiene and later changed to brown. During the subsequent post reaction stirring, the reaction mixture turned green.

The subsequent reaction with carbon dioxide corresponded to Example I. The product (10.5 parts) had an average neutralization equivalent of 101, corresponding to theoretical for 10-carbon dibasic acids. The product distribution was similar to Example I. Only 1.5 parts of polymer was obtained from the hydrocarbon fraction.

Example VI

Example I was repeated except that a total of 13.5 parts of butadiene were reacted over a period of 2 to 3 hours, using a continuous addition. 20.9 parts of product were obtained having a neutralization equivalent of 103 and having essentially the same product distribution of Example I. The hydrocarbon phase was distilled, giving only 1.2 parts of polymer.

Example VII

Example I is repeated except that isoprene is substituted for butadiene using 28 parts of the isoprene and 12.5 parts of sodium. The product is obtained in good yield and consists of C₁₂ dicarboxylic acids.

Example VIII

Example I is repeated except that a mixture of methyl-65 1,3-pentadienes is substituted for butadiene using 34 parts of the pentadiene and 12.4 parts of sodium. The product is obtained in good yields and consists of C₁₄ dicarboxylic acids.

The above examples have been repeated using methylal, ethylene glycol dimethyl ether, diethylene glycol dimethyl ether, trimethyl amine at -30° C. and similar results were obtained.

When the above examples are repeated using other alkali metals, such as potassium and lithium or alloys and mixtures of alkali metals and alkaline earth metals

such as sodium-potassium, sodium-calcium and the like, generally the same results are obtained.

The products of this process have a wide variety of uses as such and these products also can be employed as intermediates in the preparation of many other useful compounds. In particular, the dibasic acids, esters, ketones and other products produced by this invention are very valuable in the manufacture of condensation polymers, such as the nylon type, which are useful in the manufacture of fibers, films, and molded articles. These products can also be used as plasticizers for resins, synthetic lubricants and the like.

We claim:

1. The process for dimerization of a conjugated hydrocarbon polyene in the presence of an alkali metal to produce a dialkali metal polyene adduct comprising adding a conjugated polyene having between 4 and 16 carbon atoms to a reaction medium maintained at a temperature below about 50° C. containing finely dispersed alkali metal having a particle size not greater than 50 microns, between about 0.0001 and 10 percent of a diaryl ketone and at least 300 percent of an aliphatic solvent selected from the group consisting of ethers, acetals and tertiary amines, both percentages being based upon the weight of said alkali metal, said polyene being employed in a total quantity not exceeding about 1 mole per mole of alkali metal.

2. The process of claim 1 wherein the reaction mix-

ture so-formed, including said diaryl ketone, is thereafter treated with a Grignard reactant selected from the group consisting of carbonyl, thionyl and nitrile compounds.

3. The process of claim 1 wherein the polyene is a diene.

4. The process of claim 1 wherein the polyene is butadiene.

5. The process of claim 1 wherein the polyene to alkali metal molar ratio is from about 0.7:1 to about 0.95:1.

6. The process of claim 1 wherein the diaryl ketone is employed in a concentration of between about 0.001 and about 1.0 weight percent based upon the weight of the alkali metal.

7. The process of claim 1 wherein the diaryl ketone is benzophenone and the alkali metal is sodium.

8. The process of claim 2 wherein the Grignard reactant is carbon dioxide.
